UNITED STATES PATENT OFFICE.

CHARLES F. MURRAY, OF EVANSTON, ILLINOIS, ASSIGNOR TO THE FOWLER CAR COMPANY, OF CHICAGO, ILLINOIS, A CORPORATION OF ILLINOIS.

CARLINE.

1,155,365.

Specification of Letters Patent.

Patented Oct. 5, 1915.

Application filed November 18, 1912. Serial No. 731,975.

To all whom it may concern:

Be it known that I, CHARLES F. MURRAY, a citizen of the United States, and resident of Evanston, in the county of Cook and State of Illinois, have invented certain new and useful Improvements in Carlines, of which the following is a specification.

My invention relates to railway cars and has particular reference to a novel carline 10 for use in the roof construction of freight cars.

As is well known, the carline is a beam placed transversely of the car, acting as a support for the roof structure and for the 15 purpose of tying together transversely the side walls of the car. These members should be constructed with as little weight as possible consistent with the necessary strength, and, furthermore, should occupy the least 20 possible space in order to provide the necessary overhead clearance within the car. Many forms of metallic carlines have been suggested, either of commercial or special shapes, pressed or rolled, the features of 25 novelty being apparent at the ends of the carlines at the point of attachment to the side plate of the car. It is evident that a rigid connection should be made between the carline and the side plates and this without 30 unnecessary expense or the application of such parts as would increase the bulk at that point.

An object in the present construction is to provide a carline which should be readily 35 attached to the top plate by integral parts, the attaching means being readily formed without material expense.

The invention clearly stated may be said to consist of a fabricated angular member, 40 the web thereof being terminated in line with the side plates, the flanges being extended beyond the web, then bent downwardly into line providing a double attaching flange.

45 The invention will be more readily understood by reference to the accompanying drawings, wherein,

Figure 1 is a transverse section of the upper portion of a freight car having my 50 novel carline applied thereto; Fig. 2 is an enlarged section at the end; Fig. 3 is a fragmentary, enlarged perspective view of the end of the carline as it is blanked out; Fig. 4 is a similar view showing the carline in its

completed condition, and Fig. 5 is a similar 55 view from the reverse side of the carline.

Referring more particularly to the drawings, it will be seen that the sides 10 of a railway freight car are surmounted by a side plate 11, in the form of a Z-bar. The 60 roof structure is supported by my novel carline 12, this roof structure comprising the ridge beam 13, carlines 14, and roof boards 15.

The carline of my invention is preferably 65 of pressed Z-shape, with the web 16 thereof placed vertically, the flanges 17, 18, extending horizontally in opposite directions. As shown, the web 16 is terminated substantially in line with the vertical web of the 70 side plate 11, the flanges 17, 18, however, being left considerably longer, as shown in Fig. 3, then bent downwardly into line. The flanges thus bent downwardly are suitably apertured, these apertures registering 75 with corresponding apertures in the web of the side plate 11, whereby a fastening means is provided. It will be seen that such a connection is particularly strong and rigid, the maximum strength of the material being secured. Furthermore, the carline is easily 80 formed and may be by careful designing, blanked out from the metal sheet without material loss.

The construction shown is formed by 85 pressing or stamping. However, a commercial Z-bar shape might be used with equal facility. Furthermore, the exact commercial section might be changed and other modifications might be made, all without departing from the spirit of my invention, the prime consideration being that both flanges of the angular member shall have a connection to the top sill.

I claim:

1. A carline composed of a metal beam having a single vertical web and two laterally projecting flanges, said flanges being longer than the web at the ends of the beam, both said flanges being bent downward into 100 parallelism to provide means for attachment to a car side plate, substantially as described.

2. A carline composed of a metal beam having a single vertical web and two oppositely extending lateral flanges, said flanges being longer than the web at the ends of the beam, both said flanges being bent down- 105

ward into parallelism to provide means for attachment to a car side plate, substantially as described.

3. A metallic carline comprising a web 5 having flanges projecting laterally therefrom, the longitudinal dimension of each flange exceeding that of the web, the portions of the flanges which extend beyond the end of the web being bent transversely 10 across the carline and lying at substantially right angles to the planes of the main portions of the respective flanges, and also extending beyond one and the same side of the carline.
- 15 4. A metallic carline comprising a web, a top flange projecting at one side of the web and a bottom flange projecting at the opposite side of the web, the longitudinal dimension of each flange exceeding that of 20 the web, the portions of the flanges which extend beyond the end of the web being bent transversely across the carline and lying at

substantially right angles to the planes of the main portions of the respective flanges, and also extending beyond one and the same side of the carline.

5. A metallic carline comprising a web, a top flange projecting at one side of the web and a bottom flange projecting at the opposite side of the web, the longitudinal dimension of each flange exceeding that of the web, the portion of the flanges which extend beyond the end of the web being bent transversely across the carline and lying at substantially right angles to the planes of the main portions of the respective flanges, and also extending beyond one and the same side of the carline, said bent-over flange portions being disposed substantially coincident with the adjacent end of the web.
